UNITED STATES PATENT OFFICE.

PAUL ORYWALL, OF PADERBORN, GERMANY.

RESERVOIR-PEN.

No. 809,319.

Specification of Letters Patent.

Patented Jan. 9, 1906.

Application filed October 31, 1904. Serial No. 230,743.

To all whom it may concern:

Be it known that I, PAUL ORYWALL, a subject of the German Emperor, and a resident of Paderborn, Germany, have invented certain new and useful Improvements in Reservoir-Pens, of which the following is a specification.

The present invention relates to such pens in which a piece is stamped integral with the pen and bent so as to hold a small piece of hard ink.

The new feature of my invention consists therein that the pen of my construction holds the piece of ink in such a manner that the same cannot be lost or loosened.

In the accompanying drawings similar letters refer to similar parts throughout the different views.

Figure 1 shows a plan view of the pen ready to be bent. Fig. 2 shows a plan view of the pen after the piece of ink is inserted. Fig. 3 shows a section on lines I I of Fig. 2.

The pen *a* is stamped as usual, but in the form shown in Fig. 1. The overlapping piece *b* is provided with the projections *c* and *d*. The piece of hard ink *e* is inserted into the pen in the following manner: The piece of ink is laid into the hollow space formed by the pen *a*. The piece *b* is so bent around the bending-point *f* that it covers the ink. Then the pro-

jection or finger *d* is bent to overlap that side of the pen *a* just opposite of the bending-point *f*. To prevent the piece of ink from sliding out between the main part of the pen and the bent piece *b*, the four projections *c* are bent upward, so that the ink now is nearly fully covered and cannot be lost or dirtied. The pen may now be inserted into a penholder, and as soon as the pen is dipped into water it is ready to be used. The hard piece of ink *e* may be of any desired color.

What I claim as new, and desire to secure by United States Letters Patent, is—

In a writing-pen, a concavo-convex pen-body, a piece integrally connected with said body at one side and bent beneath the concave surface thereof, said piece having a projection at its free side, adapted for attachment to the pen-body and having a plurality of projections at its ends bent upwardly toward the pen-body, and a cake of solid ink, held between said piece and pen-body.

In testimony whereof I have signed my name to this specification in the presence of two subscribing witnesses.

PAUL ORYWALL.
